UNITED STATES PATENT OFFICE.

CHARLES S. MYERS, OF HAZLETON, PENNSYLVANIA.

WINDOW SCREEN.

1,417,763.

Specification of Letters Patent. Patented May 30, 1922.

Application filed September 9, 1920. Serial No. 409,091.

To all whom it may concern:

Be it known that I, CHARLES S. MYERS, citizen of the United States, residing at Hazleton, in the county of Luzerne and State 5 of Pennsylvania, have invented certain new and useful Improvements in Window Screens, of which the following is a specification.

This invention relates to improvements in 10 ventilators and more particularly to window screens.

An important object of this invention is to provide a window screen having novel means whereby the wire fabric may be readily 15 and economically renewed without the exercise of any unusual skill.

A further object of the invention is to provide a metallic screen having a wooden core to which the wire fabric is attached and 20 which by reason of being enclosed within the metallic strips from which the screen is made, is prevented from rotting or decaying.

The invention further aims to provide a 25 metallic screen which is neat in appearance, desirable in use, and cheap to manufacture.

Other objects and advantages of the invention will be apparent during the course 30 of the following description.

In the accompanying drawings forming a part of this application and in which like numerals are employed to designate like parts throughout the same,

Figure 1 is a perspective of the improved 35 screen applied,

Figure 2 is a horizontal section on the line 2-2 of Figure 1,

Figure 3 is a horizontal section taken on the line 3-3 of Figure 1,

Figure 4 is a vertical sectional view taken on the line 4-4 of Figure 1,

Figure 5 is a sectional view taken on the line 5-5 of Figure 1,

Figure 6 is a perspective of one section 45 of the screen detached,

Figure 7 is a fragmentary perspective of another section of the screen.

In the drawings, wherein for the purpose 50 of illustration is shown a preferred embodiment of the invention, the numeral 10 designates a window frame or casing within which the improved screen may be arranged.

A screen constructed according to this invention embodies coating slidably connect-

ed sections generally designated by the numerals 11 and 12, and by reason of the fact that the sections of the screen are slidably connected the screen may be readily and conveniently adjusted when arranged within the window frame.

The section 12 of the improved screen comprises a channeled frame 13 which, as illustrated in Figure 6, is of rectangular formation and U-shaped in cross section.

The frame 13 which is of metal is open in 65 one side and receives a core 14 of wood. The core 14 is also rectangular in formation and forms the attaching means for a sheet of wire fibre 15 secured to the core by tacks 16 or other suitable fastening devices. With 70 particular reference to Figure 6, it will be observed that the edge portions of the wire fabric are allowed to remain preferably flat upon the application of the screen to the frame and will not be crimped or seated 75 within grooves, which is the case with many window screens now in use. By reason of

the fact that the metal frame 13 will not yield to any great extent the wire fabric may be stretched tightly upon being secured 80

to the core and further by reason of the rigidity of the frame the core will not be allowed to warp or bend inwardly. The core 85

receiving frame 13 is adapted to be detachably arranged within an outer rectangular frame 18 so as to confine the core within the inner frame 13 and to effectively conceal 90

the tacks and the edge portions of the screening 15. The outer frame 18 which, as illustrated in Figure 4, is L-shaped in cross sec- 95

tion, snugly receives the inner frame 13 so that when assembled the section 12 will be neat in appearance and will not be possessed of any objectionable projections. The outer frame 18, the inner frame 13, and the core 14 are formed with indentations 19 which 100 serve to securely connect the parts of the section 12.

The section 11 of the improved window screen comprises an inner channeled frame 100 20 which, as illustrated in Figure 3, is U-shaped in cross section and is open in one side for receiving the core 21 preferably of wood. Since the frame 20 is of rectangular formation, the core 21 is also of rectangular 105 formation and forms an attaching means for a sheet of wire fabric 22 which is connected to the core through the medium of tacks 24

or other suitable fastening devices. The core receiving frame 20 is similar in construction to the core receiving frame 13 and is adapted to be detachably received within an outer frame 26 which, as illustrated in Figure 3, is L-shaped in cross section and comprises an inwardly extending flange 28 adapted for concealing the edge portions of the screen and the tacks 24 and a second flange 29 which extends about the sides of the inner frame.

With particular reference to Figure 3, it will be apparent that the inner frame 20 of the section 11 is flatly engaged with the inwardly extending flange 28 so that the section 12 may be positioned at one side of the section 11 and adjusted with relation to the same. A pair of the outer flanges 29 of the frame 26 are extended to form a pair of spaced parallel oppositely disposed members 30 having their longitudinal edge portions 32 extended inwardly and engaging the adjacent sides of the sections 12 so as to snugly but slidably connect the sections of the screen. It will, therefore, be noted that the flanges 29 serve not only as a means for securing the core receiving frame 20 in position but as a means for slidably connecting the sections of the screen. When the section 12 is arranged between the guide members 30 the core receiving frame 20 is securely held in position. This applies also to the core receiving frame 13 which is held within the frame 18 by the inwardly extending edge portions 32 of the guide members 30.

As illustrated in Figure 2, the several frames of the screen are formed from flat sheet metal so that the wire fabric 15 is positioned close to the adjacent side of the section 11 for providing a means whereby flies and the like are prevented from passing between the sections of the screen.

As illustrated in Figure 6, one side of the frame 13 of the section 12 is extended laterally to form a guide flange 40 which is adapted to be slidably received within one of the guide members 30. This construction makes the upper edge of the screen comparatively smooth so that when engaged by the lower portion of a sash 41, flies will be effectively excluded. With reference to Figure 4, it will be observed that the flange 40 formed at the upper edge of the section 12 has its end portion extended inwardly into engagement with the retaining frame 18 so as to cooperate with the indentations or notches 19 in holding the outer frame 18 firmly in position.

The inner frame 13 of the section 12 is provided at a point adjacent one end with a transversely extending rod 42 having its end portions extended angularly flatly along the sides of the core 14 as indicated at 44, and then inwardly and laterally to form stop elements 46 adapted to provide a means where-

by the extension of the screen will be limited. When the screen is extended the laterally projecting stop elements 46 will engage the inner end of the frame 11 and when the entire screen is contracted, the spaced stop elements 46 will engage the outer end of the frame 11. In addition to forming the stop elements, the rod 42 serves as a positive means for strengthening and reinforcing the frame 13 and also prevents the adjacent portion of the wire fabric 15 from bulging. Thus, by preventing the wire fabric from bulging, flies and the like are prevented from passing through the window between the sections of the screen.

In assembling the improved screen, the cores 14 and 21 are arranged within the core receiving frames 13 and 20 respectively and the wire fabrics 15 and 22 are subsequently tacked to the cores in the manner set forth. The core receiving frames 13 and 20 may now be arranged within the frames 18 and 26 so as to secure the cores 14 and 21 in position and to effectively conceal the edge portions of the wire fabrics and the fastening means for the same.

When desired, the wire fabric in either of the sections of the screen may be readily renewed by detaching the same from the cores. The sections of the screen may be lacquered or otherwise finished so as to give the screen a neat appearance.

In arranging my improved screen in a window, the sections of the same are extended so as to be received within the U-shaped clips 50 secured to the beading 51 of the window. As one section of the screen is offset with relation to the other section, the clips at one side of the window will be offset with relation to the clips on the other side.

In carrying out the invention, a suitable light cloth may be employed in lieu of the wire fabric so that the apparatus will be permitted to function as a ventilator adapted for arrangement in a window or the like.

With reference to the foregoing description it will be apparent that a screen constructed in accordance with this invention may be readily and conveniently adjusted to windows of various sizes and when in position will effectually keep out flies, mosquitoes and the like.

It is to be understood that the form of the invention herewith shown and described is to be taken as a preferred embodiment of the same and that such minor changes in construction and arrangement of parts may be made as will remain within the spirit of the invention and the scope of what is claimed.

Having thus described the invention, what is claimed as new is:

1. A ventilator comprising a pair of slidably connected sections one of which is provided with a frame, a foraminous body secured to said frame, and a rod traversing

said foraminous body and having its end portions secured to said frame and extended laterally to form stop elements.

2. A device of the class described including a pair of slidably connected sections, foraminous bodies secured to said slidably connected sections, and a reinforcing rod extending across one of said sections and hav-

ing its end portions secured along the sides of the same and extended inwardly and laterally to form stop elements adapted for limiting the movement of the sections with relation to each other. 10

In testimony whereof I affix my signature.

CHARLES S. MYERS. [L. s.]
